VAPOR PHASE CRACKING

Filed June 28, 1938

UNITED STATES PATENT OFFICE

2,186,585

VAPOR PHASE CRACKING

William T. Hancock, Long Beach, Calif.

Application June 28, 1938, Serial No. 216,261

4 Claims. (Cl. 196—61)

This invention relates generally to vapor phase cracking of petroleum hydrocarbons, and has for its major object to provide an improved system in which the vapors undergo efficient cracking with reduced fixed or uncondensable gas formation, and with minimum deposits of carbon.

I have discovered that it is possible to maintain within a single heating or cracking zone of a tube still, certain conditions conducive to the accomplishment of the stated object, by providing an arrangement of tubes whereby hydrocarbons first are heated to cracking temperature over a comparatively long time period while travelling an extended path of flow, and are then maintained in the same heating zone at cracking temperature during a comparatively short period while passing through a relatively short path of flow. In accordance with the invention, I provide within a single heating chamber a bank of horizontally extending tubes comprising two series connected sections or banks arranged side by side, one section being relatively wide and comprising a larger number of tubes of comparatively great aggregate length; the other section being relatively narrow and comprising a smaller number of tubes having substantially shorter aggregate length as compared with the wider section. Preferably, the heating chamber is fired from the bottom, and the hydrocarbons first flow downwardly through the wide section of the tube bank, generally counter-current to the rising combustion gases, and then pass upwardly through the narrow section of the tube bank, generally in the same direction as the combustion gas flow.

In United States Patent No. 2,034,094, issued March 17, 1936, to me on Oil cracking still, I describe a tube still that structurally is similar to the present type of still in that the tube bank comprises relatively wide and narrow sections connected in series. The patent refers to liquid phase cracking in which the oil initially flows through the narrow section of the tube bank wherein the oil is heated rapidly to cracking temperature, the oil thence flowing through the wide section of the tube bank, wherein the oil is maintained at cracking temperature over an extended period of time. I now find that in using the same type of still for vapor phase cracking, different conditions are required for most efficient conversion of the vapors and avoidance of excessive formation of fixed and uncondensable gases.

According to the present method, the hydro-

carbons are heated to cracking temperature over a comparatively long period of time during their flow through the wider section of the tube bank, the general effect being to increase the vapor temperature gradually so that overheating, with attendant fixed gas and carbon formation, are avoided at any time before the vapor temperature has been increased to the proper conversion point. The cracked vapors then flow through the narrow section of the tube bank, wherein they are maintained at cracking temperature during comparatively short periods of time sufficient to bring about reformation of the hydrocarbons, particularly the lighter and more volatile products of the cracking reaction, into heavier and recoverable constituents. In this manner, the vapors are subjected to a short interval of "soaking", which results in a substantial reformation and recovery of hydrocarbons that otherwise would be lost as uncondensable vapors.

The invention, as well as additional features and objects thereof, will be more fully understood from the following detailed description, in which reference is made to the accompanying drawing showing diagrammatically a typical form of tube still within which the vapors are subjected to cracking under the described conditions.

Referring to the drawing, the still comprises suitable brick work 10 enclosing a cracking chamber 11 separated from a preheating chamber 12 by baffle wall 13. The cracking chamber 11 preferably is fired at the bottom by suitable means, typically denoted by the burner 14, so that the hot combustion gases flow in the paths indicated by the arrows, upwardly within the cracking chamber, and then over the baffle wall 13 and downwardly through the chamber 12 to the stack outlet 15. Chamber 12 contains a bank of tubes 16 connected in series with rows of tubes 17 at an upper level within the cracking chamber, the purpose of tubes 16 and 17 being primarily to utilize residual heat of the combustion gases before their passage to the stack 18. Since tubes 16 and 17 may be used for any desired oil heating purpose, for example in topping crude or preheating oil to be vaporized for cracking, or they may be used for preheating the charging stock passing to the cracking coil. The oil enters the bottom of the tube bank 16 through inlet line 19, flows upwardly through the tubes and then through the tube rows 17, and is discharged through outlet line 20. When the charging stock is to be preheated in tubes 16 and 17, the heated

oil may be passed from line 20 through line 20a to the cracking coil feed line 24.

The cracking chamber 11 contains a bank of tubes generally indicated at 21, comprising a 5 relatively wide section or bank 21a at the right of line L-L, and a comparatively narrow section or bank 21b at the left thereof, directly between section 21a and baffle wall 13. Section 10 21a is made up of a comparatively large number of horizontally extending, series connected tubes, and section 21b of a substantially smaller number of similar series connected horizontal tubes. As illustrative, section 21a may contain 58 tubes 15 feet in length, and section 21b, including the 15 lower vertical rows of tubes 22 and 23 extending toward the bottom of the cracking chamber, may contain 96 tubes of corresponding length. As indicated by the arrows, the hydrocarbons flow 20 downwardly through section 21a, counter-current to the rising combustion gases, and then pass 25 downwardly through tubes 23 and upwardly through tubes 22 and the remaining tubes in the narrow bank above.

A suitable cracking stock, for example a gas 25 oil fraction taken from line 20a or an independent source, may be delivered through pipe 24 into a heating coil 25 in the bottom of the cracking chamber 11. In flowing through coil 25, the oil is preheated by radiant heat in the combustion 30 zone to a suitable temperature which may or may not be sufficient to partially vaporize the oil. The vapors then flow through line 26 to a second preheating coil consisting of series connected tube rows 27 and 28 within the top portion of the 35 cracking chamber. After being further superheated in tubes 27 and 28, the hydrocarbons flow through line 29 into the top row of tubes in the wide tube bank 21a. At this point the oil temperature will approach vaporizing temperature, 40 and if desired, the still may be designed and operated to give partial or complete vaporization by the time the oil enters the wide tube bank. In then flowing downwardly through the bank, the vapors are gradually heated to proper cracking 45 temperature which, for gas oil charging stock, may be around 1000° F. to 1100° F. The oil will have become completely vaporized at least by the time it reaches the lower two or three rows 50 of tubes in the wide bank, and the vapors then are heated to cracking temperature in the lower tubes exposed to the radiant heat of the combustion zone.

The vapors then are maintained at cracking 55 temperature during their comparatively short period of flow through the narrow tube bank 21b, during which time the vapors undergo reformation to the extent of substantially reducing fixed gas losses that otherwise would occur in the absence of the soaking treatment. In operation, it has been observed that the vapor temperature 60 may drop, say 50° F., during passage of the vapors through the narrow tube bank. However, the vapor temperature remains within the cracking temperature range, at which effective polymerization occurs. Leaving the narrow tube bank 21b, the vapors flow through a row of tubes 29 between tube 17 and section 21a, into discharge line 30 which may lead to any suitable apparatus within which the cracked vapors are 65 subjected to condensation and treatment for the recovery of desired fractions.

Ordinarily, the vapors will be maintained under low pressure, say below 25 lbs. per sq. in. gage, in the cracking coils, although any suitable pressure 70 may be held in the coils by a back pressure

valve 31 in the discharge line 30. It has been found from actual operation that not only does the system give highly satisfactory yields as compared with other vapor phase cracking processes, but also the conditions obtaining in the cracking coils are such that no excessive deposits of carbon occur in the tubes. Accordingly, it is possible to operate the still over long periods of time without having to shut down for carbon removal.

I claim:

1. The method of cracking hydrocarbons within a heating zone formed by horizontally spaced walls, that includes discharging incandescent combustion gases into the lower portion of the heating zone and conducting the gases upwardly within said zone, passing hydrocarbons downwardly and counter-current to the rising combustion gases in an extended path of flow through a bank a series-connected, horizontally extending cracking tubes of relatively great total length 15 and exposed within said zone to radiant heat of the combustion gases, thereby heating the hydrocarbons over a relatively long period of time at a rate sufficiently gradual to minimize fixed gas and carbon formation and at a temperature such that the hydrocarbons are cracked in vapor phase, then passing the cracked vapors upwardly through a reduced length path of flow in a bank of series-connected, horizontally extending soaking tubes having substantially less total length than said cracking tubes and located within said zone in the path of the upwardly flowing combustion gases directly between said cracking tubes and the wall of the heating zone, and reforming the vapors by maintaining them at cracking temperature during their passage through said soaking tubes and over a relatively short period of time.

2. The method of cracking hydrocarbons within a heating zone formed by horizontally spaced walls, that includes discharging incandescent combustion gases into the lower portion of the heating zone and conducting the gases upwardly within said zone, passing hydrocarbons downwardly and counter-current to the rising combustion gases in an extended path of flow through a comparatively wide bank of series-connected horizontally extending cracking tubes of relatively great total length and exposed within said zone to radiant heat of the combustion gases, thereby heating the hydrocarbons over a relatively long period of time at a rate sufficiently gradual to minimize fixed gas and carbon formation and at a temperature such that the hydrocarbons are cracked in vapor phase, then passing the cracked vapors upwardly through a reduced length path of flow in a comparatively narrow bank of series-connected, horizontally extending soaking tubes having substantially less total length than said cracking tubes and located within said zone in the path of the upwardly flowing combustion gases directly between said cracking tubes and the wall of the heating zone, and reforming the vapors by maintaining them at cracking temperature during their passage through said soaking tubes and over a relatively short period of time.

3. The method of cracking hydrocarbons within a heating zone formed by horizontally spaced walls, that includes discharging incandescent combustion gases into the lower portion of the heating zone and conducting the gases upwardly within said zone, preheating a stream of hydrocarbons by said combustion gases and then passing the preheated hydrocarbons downwardly and

counter-current to the rising combustion gases in an extended path of flow through a bank of series-connected horizontally extending cracking tubes of relatively great total length and exposed 5 within said zone to radiant heat of the combustion gases, thereby heating the hydrocarbons over a relatively long period of time at a rate sufficiently gradual to minimize fixed gas and carbon formation and at a temperature such that the 10 hydrocarbons are cracked in vapor phase, then passing the cracked vapors upwardly through a reduced length path of flow in a bank of series-connected, horizontally extending soaking tubes having substantially less total length than said 15 cracking tubes and located within said zone in the path of the upwardly flowing combustion gases directly between said cracking tubes and the wall of the heating zone, and reforming the vapors by maintaining them at cracking temperature 20 during their passage through said soaking tubes and over a relatively short period of time.

4. The method of cracking hydrocarbons within a heating zone formed by horizontally spaced walls, that includes discharging incandescent 25 combustion gases into the lower portion of the heating zone and conducting the gases upwardly

within said zone, passing a stream of hydrocarbons through a preheating space in said heating zone and then passing the preheated hydrocarbons downwardly and counter-current to the rising combustion gases in an extended path of flow through a bank of series-connected horizontally extending cracking tubes of relatively great total length and exposed within said zone to radiant heat of the combustion gases, thereby 10 heating the hydrocarbons over a relatively long period of time at a rate sufficiently gradual to minimize fixed gas and carbon formation and at a temperature such that the hydrocarbons are cracked in vapor phase, then passing the cracked vapors upwardly through a reduced length path 15 of flow in a bank of series-connected, horizontally extending soaking tubes having substantially less total length than said cracking tubes and located within said zone in the path of the upwardly flowing combustion gases directly between 20 said cracking tubes and the wall of the heating zone, and reforming the vapors by maintaining them at cracking temperature during their passage through said soaking tubes and over a relatively short period of time.
